(57) **CLAIM**

We claim the ornamental design for a beverage can insulator, as shown and described.

DESCRIPTION

FIG. 1 is a perspective view of a beverage can insulator in a cylindrical configuration, showing my new design;

FIG. 2 is a front elevational view of the invention in a flat configuration;

FIG. 3 is a rear elevational view of the invention in the flat configuration;

FIG. 4 is a left-side elevational view of the invention in the flat configuration;

FIG. 5 is a right-side elevational view of the invention in the flat configuration;

FIG. 6 is a top plan view of the invention in the flat configuration; and,

FIG. 7 is a bottom plan view of the invention in the flat configuration.

The broken lines showing a beverage can in FIG. 1 are included for the purpose of illustrating the invention in use, and form no part of the claimed design.
